UNITED STATES PATENT OFFICE.

TELESPHORE J. SENESAC, OF CHICAGO, ILLINOIS.

CONCRETE FORM.

Application filed February 14, 1927. Serial No. 167,880.

This invention relates to metallic forms for use in the pouring of concrete beam and floor construction. The object of the invention is to provide a set of forms which may be easily assembled or disassembled, and which may be variably adjusted to differences in the spacing of concrete beams so that a single cost of forms may be employed under diverse conditions. A further object of the invention is to so provide the forms that they will be mutually self-supporting, so that the danger of bending or distortion under the concrete load is avoided.

15 Further objects and details will appear from a description of the invention in conjunction with the accompanying drawings wherein—

Figure 1 is a perspective view of a floor 20 under construction employing the forms of the present invention;

Fig. 2 is a similar view showing forms of a slightly modified character;

Fig. 3 is a perspective view of one of the 25 end main forms of the series;

Fig. 4 is a similar form of one of the intermediate main forms of the series;

Fig. 5 is a similar view of one of the supplemental end forms;

30 Fig. 6 is a similar view of one of the intermediate end forms;

Figs. 7, 8, 9 and 10 are perspective views showing a set of forms of slightly modified construction;

35 Fig. 11 is an enlarged cross sectional view showing the form arrangement exemplified in Figs. 1, 7, 8, 9 and 10; and

Fig. 12 is a cross sectional view showing the form arrangement exemplified in Figs. 40 2, 3, 4, 5, and 6.

Referring to the forms shown in Fig. 1, each set of forms comprises a pair of main end forms 12 of box-like construction having parallel side walls 13, a top wall 14, and a single end wall 15, the bottom and one end being left open. One of the forms 45 12 is located at each end of a series in telescoping arrangement with respect to one or more intermediate forms 16 shown in detail in Fig. 10. The intermediate forms comprise parallel side walls 17 and a top cross wall 18, the intermediate forms being open at each end and at the bottom. In conjunction with the main forms 12 and 16 50 is a series of supplemental forms 20. Each supplemental form comprises a top cross wall 21, a single side wall 22 and an end wall 23, and each of the intermediate supplemental forms, as shown in Fig. 7, comprises a top wall 24 and a single side wall 60 25 constituting in effect an angle plate without ends.

The arrangement is one which permits the main forms in the series to lie in end-wise telescoping relation to one another with 65 a series of supplemental forms constituting a lateral extension to the main series with their top walls in overlapping relation with the top walls of the main series. The end forms of each series being provided with 70 end walls constitute a closure at each end of each form series, and the side walls of the main forms on the side adjacent to the supplemental forms constitute a continuous 75 center reinforcing wall for supporting the entire form structure centrally from end to end. The arrangement is one which permits of a wide variation both in the length and in the width of the form series, and the forms being made of comparatively thin, 80 though relatively firm, sheet metal, the overlaps will not introduce any appreciable shoulders or ridges in the poured concrete.

The modified forms shown in Figs. 2, 3, 4, 5, and 6 differ from those previously 85 described only in the provision of the flanges 26 along the margins of the side walls, the construction and arrangement of the forms being otherwise identical with that heretofore described. The main forms of the series 90 are provided along the inner angle between the side and top walls with a nailing strip 27 above which the form is provided with a series of slots or apertures 28 which expose the wooden strip and furnish a nailing surface for the reception of tacks 29 which are entered through selected nail holes 30 arranged in transversely extending rows, the arrangement being such that the supplemental forms lap over the main forms the 95 desired extent and are nailed through the holes which happen to register with the slots 28, which arrangement serves to unite the forms and hold the outer side walls of the associated forms in properly spaced relation 100 with respect to one another. This permits the side walls of the forms to stand in vertical relation to the top walls so that the cement when poured will furnish truly vertical beams having parallel side walls, thereby 105 effecting economy in the use of cement as compared with the employment of forms 110

having upwardly converging side walls which are frequently provided to assist in the removal of the forms after the setting of the cement.

- 5 In setting up the forms of the unflanged series first described, wooden joists 31 are set up in spaced relation immediately below the position to be occupied by the cement beams, and each of the joists is provided along its 10 top with a cross rail 32 which furnishes a base form for the lower edge of the concrete beam. On each side of each joist, in spaced relation with the top rail, is a furring strip 33 which furnishes a ledge for the support of 15 a series of cross beams 34 each provided near each end with a spacing block 35.

The lower edges of the outer side walls of the assembled forms rest between the blocks 35 and the adjacent edge of the rail 32, and 20 are thus held against displacement. The intermediate side walls of the main forms of the series rest directly upon and are supported by intermediate portions of the cross rails, and with the form set up in the manner 25 indicated, the cement is poured. After the cement is set, the cross rails 34 may be easily removed by swinging their ends sufficiently to disengage them from contact with the furring strips after which the lower edges 30 of the lower side walls may be sprung inwardly sufficiently to disengage the form as a whole and permit its easy removal. In case difficulty is experienced in removing the forms, the main forms may be pulled away 35 from the tacks which are nailed into the nailing strips 27, so that in no case will any difficulty be experienced in removing the form.

In setting up the forms illustrated particularly in Figs. 2, 3, 4, 5, 6 and 12, the flanges 40 26 are secured directly by tacks 36 to the rails 37 and 38, as best indicated in Fig. 12, but in other respects the setting of the forms follows the practice first indicated.

45 The arrangement of the forms is one which enables them to be easily and cheaply constructed of sheet material and permits a large number of forms to be nested together for shipment. The construction is one which 50 permits forms of standard size to be readily employed under diverse conditions and to readily conform to such spacing arrangement of the beams as may be required.

I claim:

55 1. In forms for pouring plastic materials, a main form having spaced side walls and a top cross wall, and a supplemental form having a single side wall and a top wall adapted to overlap the top wall of the main form, substantially as described.

60 2. In forms for pouring plastic materials, a main form having spaced side walls and a top cross wall, a supplemental form having a single side wall and a top wall adapted to overlap the top wall of the main form, and

means for securing the overlapped top walls against displacement, substantially as described.

3. In forms for pouring plastic materials, a main form having spaced side walls and a top cross wall, a supplemental form having a single side wall and a top wall adapted to overlap the top wall of the main form, and a nailing strip secured within the angle between one of the side walls and the top wall 75 of the main form, and securing means nailed through the overlapped top wall of the supplemental form and into said nailing strip, substantially as described.

4. In forms for pouring plastic material, 80 the combination of a plurality of main forms of box-like formation each having parallel side walls and a top cross wall, the main forms lying in endwise telescoping relation to one another, a plurality of supplemental 85 forms of angle formation each having a single side wall and a top wall, the supplemental forms lying in endwise telescoping relation to one another and having their top walls in overlapping relation with respect to 90 the top walls of the main forms, substantially as described.

5. In forms for pouring plastic materials, the combination of a plurality of main forms of box-like formation each having parallel 95 side walls and a top cross wall, the main forms lying in endwise telescoping relation to one another, a plurality of supplemental forms of angle formation each having a single side wall and a top wall, the supplemental forms lying in endwise telescoping 100 relation to one another and having their top walls in overlapping relation with respect to the top walls of the main forms, and means for securing the overlapping top walls together, substantially as described.

6. In forms for pouring plastic materials, the combination of a plurality of main forms of box-like formation each having parallel side walls and a top cross wall, the main 110 forms lying in endwise telescoping relation to one another, a plurality of supplemental forms of angle formation each having a single side wall and a top wall, the supplemental forms lying in endwise telescoping 115 relation to one another and having their top walls in overlapping relation with respect to the top walls of the main forms, means for securing the overlapping top walls together, said means including nailing strips secured 120 within the main forms in contact with the top walls thereof, and tacks nailed through the overlapping top walls and into said nailing strip, substantially as described.

7. In forms for pouring plastic materials, 125 the combination of a plurality of main forms of box-like formation, each having spaced parallel side walls and a cross top wall, forms lying in endwise telescoping relation to one another, a plurality of supplemental forms 130

each having a single side wall and a top wall, the supplemental forms lying in endwise telescoping relation to one another and having their top walls in overlapping relation with respect to the top walls of the main forms, means for securing the overlapped top walls together, a plurality of form supports adapted each to furnish a base for the pouring of concrete beam, each of said supports being formed to furnish a side groove or channel, a plurality of cross rails bridging the space between said grooves or channels and having their ends entered thereinto, said rails furnishing supports for the lower edges of the side walls of the main and supplemental forms, and means on said rails bearing against the inner lower margins of the outermost side walls of the series, substantially as described. 15
